DESIGN FOR A PLAQUE OR SIMILAR ARTICLE

Walter Scott Benners, Elizabeth, N. J., assignor to New Jersey State Funeral Directors Association, Inc., Newark, N. J., a corporation of New Jersey

Application October 19, 1939, Serial No. 87,732

Term of patent 14 years

To all whom it may concern:

Be it known that I, Walter Scott Benners, a citizen of the United States, and a resident of Elizabeth, in the county of Union and State of New Jersey, have invented a new, original, and ornamental Design for a Plaque or Similar Article, of which the following is a specification, reference being had to the accompanying drawing, forming part thereof.

The drawing is lined for color.

I claim:

The ornamental design for a plaque or similar article, as shown and described.

WALTER SCOTT BENNERS.
